UNITED STATES PATENT OFFICE.

WALTER THOMAS SMITH, OF CORNELL, WISCONSIN, ASSIGNOR TO CORNELL WOOD PRODUCTS COMPANY, OF CORNELL, WISCONSIN, A CORPORATION.

SCRAPER-BAR SUPPORT FOR PASTING-MACHINES.

1,311,721.

Specification of Letters Patent. Patented July 29, 1919.

Original application filed April 25, 1918, Serial No. 230,770. Divided and this application filed April 28, 1919. Serial No. 293,270.

To all whom it may concern:

Be it known that I, WALTER THOMAS SMITH, a citizen of the United States, residing at Cornell, in the county of Chippewa and State of Wisconsin, have invented certain new and useful Improvements in Scraper-Bar Supports for Pasting-Machines; and I do declare the following to be a full, clear, and exact description of the invention, such as will enable others skilled in the art to which it appertains to make and use the same.

The present application is a division of my U. S. application Serial No. 230,770, filed April 25, 1918, and allowed February 15, 1919. The present case is devoted to the supports of the scraper bar.

The principal object of the invention is to provide a simple and inexpensive form of hanger for attachment to pasting machines of ordinary construction, to hold a four sided scraper bar in position for presenting two opposed corners thereof for simultaneous contact with two plies of paper to separate them and remove surplus paste.

With the foregoing in view, the invention resides in the novel construction and arrangement of parts hereinafter described and claimed, reference being made to the accompanying drawing:

Figure 1 is an end elevation of a pasting machine showing the application of the hangers for supporting the scraper bar.

Fig. 2 is a side elevation showing more clearly the arrangement of the hangers with respect to the old and well known parts of the pasting machine.

Fig. 3 is a perspective view of the scraper bar and its hangers.

In the drawings above briefly described, a pasting machine M is shown constructed in the same manner as set forth in the parent application Serial No. 230,770, above referred to, and it is unnecessary to describe the several details of the machine, although it may be well to state that it provides means for pasting two plies 1 of paper or the like together, utilizes a four-sided scraper bar 2 for separating said plies after pasting and employs rollers or the like 3 for again forcing the plies together after surplus paste has been removed by said scraper bar 2. The

present invention resides specifically in the hanger bars 4 for the bar 2 and consequently the description is confined more particularly to these parts.

The hanger bars 4 are provided with horizontal upper ends 5 adapted for attachment to well-known bearings B at the upper end of the pasting machine M, said bars inclining downwardly and laterally from said horizontal ends 5 and having their lower ends bent outwardly at 6 at right angles to the inclined parts of said bars, and then bent upwardly at 7 in parallel relation with said inclined portions. Hook-shaped sockets are thus provided to receive the ends of the scraper bar 2 and due to the inclination of the bars 4 and the relation of the parts 6 and 7 therewith, two edges of said scraper bars will be presented to the plies 4. Bolts 8 pass through the upturned bar ends 7 and through the inclined body portions of said bars and are positioned above the scraper bar 2, and tightening of said bolts 7 will tightly clamp the ends of said scraper bar in place.

By constructing the hangers 4 in the novel manner shown, they may be quickly attached to pasting machines of well known construction and may be manufactured at small cost. Furthermore, the novel formation at the lower ends of said hangers, will not only permit tight clamping of the scraper bar, but will allow this bar to be removed, turned to present new scraping edges to the work, and then again secured in place.

Since probably the best results are obtainable from the exact construction and arrangement shown, it may well be followed but within the scope of the invention as claimed, numerous minor changes may well be made.

I claim:

1. The combination with the four-sided scraper bar of a pasting machine, of a pair of inclined hanger bars for said scraper bar, the upper ends of said hanger bars being adapted for attachment to the pasting machine, while their lower ends are bent laterally at right angles to the inclined portions of said bars and then upwardly in parallel relation with said inclined portions, thus forming hook-shaped poly-sided sockets re-

ceiving the ends of said scraper bar, and bolts passing through said upwardly bent bar ends and through the inclined body portions of said bars, above said scraper bar, for clamping the latter tightly in place.

2. A structure as specified in claim 1, said upper ends of said hanger bars being bent

horizontally in the opposite direction from the lower ends of said bars and provided with openings to receive attaching bolts. 10 In testimony whereof I have hereunto set my hand.

WALTER THOMAS SMITH.
